UNITED STATES PATENT OFFICE.

CAROLINE BARD TOMPKINS, OF JERSEY CITY, NEW JERSEY, ASSIGNOR OF ONE-FOURTH
TO LEON MYLES, OF BAYONNE, NEW JERSEY.

WASHBOARD.

973,320.

Specification of Letters Patent. Patented Oct. 18, 1910.

Application filed September 10, 1909. Serial No. 517,007.

To all whom it may concern:

Be it known that I, CAROLINE BARD TOMPKINS, a citizen of the United States of America, residing at Jersey City, in the county of Hudson and State of New Jersey, have invented an improvement in Washboards, of which the following is a specification.

My invention relates to improvements in wash-boards, and its object is to provide a wash-board that can be readily knocked down for economizing space in the house when not in use, also for economizing space in transportation, and for convenience in carrying by hand from place to place, and it consists principally of two sections or members with means for holding them together to form a whole in an operative position, and also for holding the two members or sections together in a knock-down position by the same means or device by which they are held in an operative position.

In the accompanying drawing, Figure 1 is a front elevation of a wash-board constructed according to my invention and with the two members or sections clamped together in an operative position. Fig. 2 is a section at the line x , x , of Fig. 1. Fig. 3 is a side elevation of the same, and Fig. 4 shows the board after it has been knocked down, and the two members or sections placed together in a position for economizing space or for transportation.

1 and 2 are side-bars; these are connected by a top cross-bar 3 and lower cross-bar 4 and form the frame of the wash-board. The side-bars 1 and 2 are divided transversely and their divided ends are preferably rabbeted as at 5 and 6 so that they will overlap and form a close and smooth joint when brought together to form a whole.

Instead of employing the common ribbed or fluted surface over which clothes are rubbed to cleanse them, I prefer to employ a series of rollers 7 although it will be apparent that my invention is applicable to a wash-board having either rubbing surface. These rollers 7 may be plain wood, or wood covered with india-rubber or non-corrosive substance, or they may be entirely of metal. I prefer plain wooden rollers. These rollers 7 are held in position in the frame by means of axes 8 revolving in bearings 9 in the side-

bars 1 and 2. The axes 8 are preferably formed integral with the rollers 7. 55

To give additional strength to the two members, especially when separated from each other, or in a knocked-down condition, I prefer to make use of cross-rods 10 and 11. 60

The side-bars 1 and 2 are provided with a central longitudinal slot extending a desired distance from their meeting ends so that when the ends of the side-bars 1 and 2 of the respective sections are over-lapped and brought together, there is a continuous 65 slot in the center of each side-bar extending some distance either side of the center of the frame.

I prefer to make the division in the board at the point illustrated in the drawing, so 70 that when the board is knocked down, the two sections can be placed together in the most compact form as shown in Fig. 4.

The two sections of the wash-board are held together in a position for use by suitable means. I have shown and prefer to make use of a thumb-screw 13 and clamping plate 14 at each side of the board upon the respective side-bars. The head of each thumb screw 13 is knurled to assist the 75 grasp, and its base is spread of a width corresponding to the width of the side-bars 1 and 2 upon which it rests in use. The stems 15 are screw-threaded and of a size 80 to pass through the slots 12 in the side-bars 85 1 and 2 and slide therein, and these stems screw into the clamping-plates 14 which are on the opposite or rear side of the frame.

When the two sections of the wash-board are brought together with the rabbeted ends 90 of the side-bars overlapped, it will be readily understood that when the thumb-screws 13 and clamping plates 14 are applied and screwed to place, the two sections will be firmly held together, and that the 95 wash-board will be complete and ready for use; and that when the board is no longer required for immediate use, it can be readily knocked down by turning the knurled heads 100 of the screws 13 to the left thus loosening the clamping devices when the two sections of the board may be separated, after which they may be placed together in the compact form shown in Fig. 4 and secured in that 105 position by the screws 13 and clamping plates 14. It will thus be seen that the thumb-

screws 13 and clamping plates 14 are adapted to perform two functions, that is, to hold the two sections of the board together in position for use, and also to hold them together after being knocked down and placed in the position shown in said Fig. 4, in which condition they occupy considerable less space in the house or in transportation, and are in a convenient form for carrying by hand from place to place.

At or near the top of the upper section of the wash-board, I prefer to employ a box or receptacle 16 for soap or other articles, which box is provided with a sliding cover 17 and may be divided if desired, by a partition 18 shown by dotted lines in Fig. 1. The sliding cover 17 of the box 16 may have a notch 19 at or near its forward end to facilitate the withdrawal of the cover from the grooves 20 in the box in which it slides. I do not however wish to limit myself to this particular construction of receptacle, as it will be readily understood that any desired character of receptacle for soap or like articles may be employed with my invention.

I claim as my invention;

1. A wash-board divided transversely through the rubbing board and side-bars of the frame, thus forming two sections, and provided with means performing the double function of holding the two sections together in an operative position, and for

holding said sections together in a compact form for economizing space when the wash-board is not in use.

2. A wash-board composed of two sections, the meeting ends of which are rabbed, and means for securing such sections together.

3. In a wash-board composed of two sections, the meeting ends of which are rabbed, the combination of thumb-screws and clamping-plates by which means the two sections are secured together.

4. A wash-board comprising two sections, each having slotted side bars which are divisible and constructed with meeting ends that are similar and fit for the continuity of the side bars, and clamping means operative through the slots in the side bars and by which means the two sections of the board are held together.

5. In a wash-board composed of two sections, the combination of slotted side-bars and clamping means operative through the slots in the side-bars and by means of which the two sections of the board are held together.

Signed by me this 7th day of September 1909.

CAROLINE BARD TOMPKINS.
